UNITED STATES PATENT OFFICE.

WALTER S. MORTON, OF NEW YORK, N. Y., ASSIGNOR TO CHESHIRE KITCHENS, INC.,
OF NEW YORK, N. Y., A CORPORATION OF DELAWARE.

PROCESS AND APPARATUS FOR DEHYDRATING.

Application filed March 21, 1922. Serial No. 545,519.

My invention relates to devices for dehydrating various materials and to a process of dehydrating capable of being carried out by that device. More particularly my invention relates to apparatus and process for effecting the dehydration of food products.

I have found from experiments that in dehydrating materials, particularly food products, the dehydration is carried out more efficiently when the material to be dehydrated exists in relatively small particles and is spread out in relatively thin layers.

15 I have also found that when the dehydrating medium, be it heated or cold air or other gas, is forced through the material to be dehydrated with sufficient rapidity and in such quantity that the particles of the material are agitated by the passage of the medium very desirable results will be obtained.

20 I have also found that when the dehydrating medium is successively passed through a series of material supporting partitions which extend across a passage through which the medium is forced, the rate and extent of dehydration are susceptible of complete control. A rotational rearrangement of the partitions through which the medium successively passes also assists in the control of the dehydrating. This rotational rearrangement may consist in removing the partition with the material 25 carried thereby through which the medium first passes and adding a partition containing nondehydrated material as the last partition through which the medium passes, or it may consist in removing the first partition 30 through which the medium passes and placing it where the medium will pass through it last. I have also found that it is highly desirable to weigh the material which is being dehydrated without removing it from the dehydrator and that it is advantageous to continue the operation of the dehydrating device during the weighing of any given quantity of material being acted upon 35 thereby.

It is an object of my invention to provide 50 apparatus and process for securing simultaneously or separately various advantages and benefits above enumerated.

Further objects and advantages will appear from the following description taken 55 in connection with the accompanying drawings forming part thereof and in which,

Fig. 1 is a front elevation of a dehydrator embodying my invention.

Fig. 2 is a top plan view of the construction shown in Fig. 1.

Fig. 3 is a sectional view on the line 3—3 of Fig. 1, and

Fig. 4 is a detailed view.

Referring to the drawings which show by way of exemplification one embodiment of my invention it will appear that a power driven fan or blower 1 provides for the circulation of the dehydrating medium which may be heated or cooled by fluid passing through the coils 2. The medium is supplied to a conducting chamber 3 which is provided with openings 4 at intervals along its length. Around each opening is placed packing material 5 for a reason hereinafter 60 disclosed. Communicating with and positioned over each opening 4, there is a passage 6 for the dehydrating material within which are closely positioned partitions 7 for supporting the material to be dehydrated. 65 Each of the passages 6 contains a series of frames 8 one of which is shown in Fig. 4. Each frame comprises side and end members and has extending across it a relatively strong partition member 9 which may be wire screening, over which is preferably extended a material 10 of relatively finer mesh which may be cheese cloth or scrim. Around each frame extends a strip of packing material 11, so that when the frames are 70 placed one upon another and the series of frames is placed upon the chamber 3 over the opening 4 and in contact with the packing 75 5, a passage 6 is formed which is comparatively air tight except that it is open at its ends; and this passage has an air tight connection with the chamber 3; by reason of the packing material 5.

In carrying out my process the material to be dehydrated is reduced to small particles if it does not exist in that form and placed in thin layers upon the partitions 7 5 carried by the various frames 8. The frame is then weighed and taking into consideration the amount of tare the final weight after dehydration can be ascertained from data obtained by previous experiments. The material is spread out in thin layers on the partitions and the frames are placed one upon the other. The dehydrating medium then passes successively through the partitions and the material thereon as it issues 10 from the chamber 3 through the openings 4. It is passed with such rapidity that the material is agitated and the medium acts upon all surfaces of the particles. In order that the extent of dehydration may be ascertained I have provided doors 12 supported from a member 13 extending across each opening 4 and swinging up into contact with the packing 14 which surrounds the opening 4 which is thus divided into two 15 parts. The said doors are closed when it is desired to ascertain the extent of dehydration. These doors will cut off the flow of the dehydrating medium and they are both closed from the front of the dehydrator by 20 pulling upon the ropes 15 and 16. The rope 17 may be used for opening one of the doors after which the other will ordinarily open by gravity, when its retaining rope is unfastened, due to the fact that the force of 25 the dehydrating medium finds an outlet through the door already open. The ropes 15 and 16 are fastened upon the cleats 18 when the doors are closed. These cleats are shown, respectively, in the left and right 30 hand sections of Fig. 1. Vertical frame members 19 extend upwardly from the corners of each opening 4 and rods 20 slide upon them being guided by staples or eyes 21, the lower end of each rod 20 is provided 35 with projection 22 and the upper end is provided with a similar projection 23 turned 45° from the projection 22. Links 24 connected respectively to the projections 23 are joined by a lever 25 secured to a rod 26 40 which passes from the front of each section of the hydrator to the back so that the rods 20 at both front and back will be simultaneously operated. It will be apparent that when the projections 22 are brought to the 45 proper level while they project outwardly from the hydrator as shown in connection with the right hand section of the hydrator in Fig. 1 they may be raised to a position adjacent the handles 8' of any of the frames 50 8 by mechanism hereinafter described and then swung in under those handles by moving the lower end of the lever 25 to the right. Extending upwardly from each rod 20 is a rope or cable 27 which passes over a

65 pulley 27' to a drum 28, one drum being provided at each side of each section and the two drums for each section being connected by a rod 29 to which is secured a lever 30 actuated by a cord 31. In order to separate the upper frames from the frame which first receives 70 the dehydrating medium the cord 31 is drawn down until the projections 22 are just below handles 8' of the frame next to the bottom and then the bottom of the lever 25 is swung to the right to swing the projections 22 in under the handles 8' of the frame next to the bottom and the cord 31 is drawn down further to raise the frames which formerly rested upon the bottom frame. The bottom frame may be then removed for weighing to ascertain the degree of dehydration or it may be placed upon the top of the series of frames to carry out a rotational rearrangement of the frames. In order to avoid removing the bottom 75 frame for weighing I provide rods 30' on each side of each passage 6 which are guided by vertical members 31' positioned intermediate the corner posts 19 and which have arms 32 projecting beneath the sides of the 80 bottom frame. To the top of rods 30' are connected cords 33 which are attached to the arms 34 which are pivoted upon the rod 35 and brought together at 36. A scale 37 is attached at the junction 36 and has attached 85 to its movable member a cord 38. It will now be apparent that after the upper frames are lifted off a pull on the cord 38, extensive enough to lift the bottom frame upon the arms 32, will indicate upon the scale 37 90 the weight of the bottom frame and its contents. From data previously ascertained the degree or completion of the dehydration of the material on that frame becomes known. If the dehydration is complete the bottom 95 frame is removed, the series of frames lowered down over the opening 4 and the top frame which preferably contains no material but merely acts as a cover to keep the material from being blown out, is removed 100 and a frame containing nondehydrated material is placed upon the top of the series after which the cover is replaced. It will be apparent from the foregoing that I have provided means for selectively lifting up 105 different numbers of frames for the replacement or rotational rearrangement of those frames or for the weighing while in position on the dehydrator of one or more of the frames. After a series of frames has been rearranged and restored to position the doors 12 are opened and the dehydrating 110 process continued. One section being rearranged at a time, it will be apparent that the operation of the dehydrator is continuous. 115

120 While I have described one embodiment of my invention in great detail, I do not 125

intend that my invention shall be limited to the specific features thereof, but that it shall be defined by the hereunto appended claims.

What I claim as new and desire to secure by Letters Patent is:

1. In a dehydrator, a conducting chamber for the dehydrating medium and provided with an opening, a series of frames arranged over said opening which are provided with foraminated partitions for supporting the material to be dehydrated, and means for providing an air-tight closure for said opening. 10
2. In a dehydrator, a conducting chamber for the dehydrating medium and provided with an opening, a series of frames arranged over said opening which are provided with foraminated partitions for supporting the material to be dehydrated, and means for providing an air-tight closure for said opening, part of said means being operable from the front of the dehydrator. 20
3. In a dehydrator, a conducting chamber for the dehydrating medium and provided with an opening, a series of frames arranged over said opening which are provided with foraminated partitions for supporting the material to be dehydrated, and means for providing an air-tight closure for said opening, said means including a door which may be opened or closed by a rope projecting through the front of the dehydrator. 30
4. In a dehydrator, a conducting chamber for the dehydrating medium and provided with an opening, a series of frames arranged over said opening certain of which are provided with foraminated partitions for supporting the material to be dehydrated, each of said frames adapted to form sealed joints with its adjacent frames, and an air tight closure for said opening including a door which may be operated by a rope projecting through the front of the dehydrator. 40
5. In a dehydrator, a conducting chamber for the dehydrating medium and provided with an opening, a series of frames arranged over said opening certain of which are provided with foraminated partitions for supporting the material to be dehydrated and means whereby a frame and its contents may be weighed without removal from the dehydrator. 50
6. In a dehydrator, a conducting chamber for the dehydrating medium and provided with an opening, a series of frames arranged over said opening certain of which are provided with foraminated partitions for supporting the material to be dehydrated, means for lifting certain of said frames and means for weighing the remaining frame or frames without removal from the dehydrator. 60
7. In a dehydrator, a conducting chamber for the dehydrating medium and provided with a plurality of openings, a series of frames arranged over said openings and provided with removable foraminated partitions for supporting the material to be dehydrated, each of said frames adapted to form sealed joints with its adjoining frames, and means for closing said openings separately to permit continuous operation. 70
8. In a dehydrator, a conducting chamber for the dehydrating medium and provided with a plurality of openings, a series of frames arranged over said openings and provided with removable foraminated partitions for supporting the material to be dehydrated, each of said frames adapted to form sealed joints with its adjoining frames, and means for closing said openings separately to permit rearrangement of the frames over either of said openings. 75
9. In a dehydrator, a conducting chamber for the dehydrating medium and provided with a plurality of openings, a series of frames arranged over said openings and provided with removable foraminated partitions for supporting the material to be dehydrated, each of said frames adapted to form sealed joints with its adjoining frames, and means for providing air-tight closures for said openings, said means including doors which may be opened or closed from in front of the dehydrator. 80
10. In a dehydrator, a conducting chamber for the dehydrating medium and provided with an opening, foraminated partitions dividing said opening into a plurality of relatively broad and shallow compartments, and means for supplying a dehydrating medium to said opening and successively through said partitions with sufficient force and quantity to agitate small particles of material to be dehydrated supported upon said partitions, and doors for cutting off the supply of the dehydrating medium which are operated from in front of the dehydrator. 100
11. The process of dehydrating consisting in reducing the material to be dehydrated to small particles, arranging the material in a thin layer and forcing a dehydrating medium through said thin layer of material with sufficient rapidity to agitate said particles to expose them on all sides to said dehydrating medium. 105
12. The process of dehydrating consisting in arranging in a plurality of thin layers material to be dehydrated in small particles, passing a dehydrating medium successively through said layers with sufficient force to agitate said particles and rearranging said layers in rotation. 110
13. The process of dehydrating consisting in arranging in a plurality of thin layers material to be dehydrated in small particles, passing a dehydrating medium successively through said layers with sufficient force to agitate said particles and adding layers of 120
14. The process of dehydrating consisting in arranging in a plurality of thin layers material to be dehydrated in small particles, passing a dehydrating medium successively through said layers with sufficient force to agitate said particles and adding layers of 125
15. The process of dehydrating consisting in arranging in a plurality of thin layers material to be dehydrated in small particles, passing a dehydrating medium successively through said layers with sufficient force to agitate said particles and adding layers of 130

undehydrated material as the last layer to be acted upon by the medium as layers first acted upon by the medium are removed upon completion of dehydration.

5 14. In a dehydrator, means for supplying a dehydrating medium to a passage, said passage formed by means of a series of removable frames having foraminated parti-

tions in said frames, single means to raise and hold a determinable number of said frames, and means for weighing the remaining frame or frames.

In testimony whereof, I have signed my name to this specification.

WALTER S. MORTON.
